CONTROL PANEL OF AN INTERCOMMUNICATION SYSTEM

Chauncey E. Waltman, Chicago, Ill., assignor to NuTone,
Inc., Cincinnati, Ohio, a corporation of New York

Application April 9, 1958, Serial No. 50,404

Term of patent 14 years

(Cl. D26—14)

FIG. 1.

FIG. 2.

FIG. 3.

Figure 1 is a front view of the control panel of an intercommunication system incorporating my new design.

Figure 2 is a transverse cross sectional view through one of the control knobs appearing in the lower part of the design, all three of these knobs being identical.

Figure 3 is a transverse cross sectional view through the large control knob appearing at the right center of Figure 1.

The broken line showing of legible matter in the drawing is for illustrative purposes only.

I claim:

The ornamental design for a control panel of an intercommunication system, substantially as shown and described.
